(57) **CLAIM**

The ornamental design for a hand scraper, as shown and described.

DESCRIPTION

FIG. 1 is a front elevation view of a hand scraper showing my new design, the rear elevation being a mirror image thereof;

FIG. 2 is a top plan view thereof, a bottom plan view thereof being identical;

FIG. 3 is a left side elevation view thereof;

FIG. 4 is a right side elevation view thereof; and,

FIG. 5 is a bottom, left, front perspective view thereof.

The broken line showing is for the purpose of illustrating unclaimed portions of the article and forms no part of the claimed design.

1 Claim, 4 Drawing Sheets
